Wiedenhein & Fairbanks

ATTORNEYS.

UNITED STATES PATENT OFFICE.

THOMAS O. SCHRADER, OF ALLENTOWN, PENNSYLVANIA, ASSIGNOR TO DENT HARDWARE CO., OF FULLERTON, PENNSYLVANIA, A CORPORATION OF PENNSYLVANIA.

LATCHING DEVICE FOR REFRIGERATOR DOORS.

Application filed July 14, 1925. Serial No. 43,475.

- This invention, generally stated, relates to a latching device for refrigerator or like doors and has more especial relation to a latching device in which the operating handle is longitudinally extended and which the latching door is arranged in parallelism therewith and is provided at its working end with a roller for engaging a keeper upon the refrigerator casing.
- 10 The leading object of the present invention is to provide a latching device of the character stated which is of simple, inexpensive, efficient, and positive construction and which is especially adapted for use in connection with soda-water fountains where the attendants in charge have to act quickly and usually are carrying glasses or the like at the time it is necessary for them to open and close refrigerator doors.
- 15 A further object of the present invention is to provide general details of construction and arrangement and combination of parts for attaining the results sought by the leading object.
- 20 Other and further objects not at this time appearing will appear hereinafter.

The invention consists of the novel construction hereinafter described and finally claimed.

25 The nature, characteristic features and scope of the invention will be more fully understood from the following description taken in connection with the accompanying drawings forming part hereof, and in which:

30 Fig. 1, is a fragmentary view in front elevation of a refrigerator or like casing provided with a keeper and a door provided with a latching attachment the said view illustrating the parts in latched position.

35 Fig. 2, is a view in longitudinal section taken upon the line 2—2 of Fig. 1.

Fig. 3, is a view in rear elevation of the latching attachment detached from the door.

40 Fig. 4, is a view in longitudinal section of the latch bar; and

Fig. 5, is a view in elevation of the keeper detached.

45 For the purpose of illustrating my invention I have shown in the accompanying drawings one form thereof which is at present preferred by me, since the same has been found in practice to give satisfactory and reliable results, although it is to be understood that the various instrumentalities of which my invention consists can be va-

riously arranged and organized and that my invention is not limited to the precise arrangement and organization of the instrumentalities as herein shown and described.

Referring to the drawings in detail the reference numeral 1 designates the casing or housing of a refrigerator or the like and the reference numeral 2 designates a door having hinged connection therewith. Carried by the door 2 is a casing 3 secured to the door 2 by means of screws 4. This casing 3 is open at its rear as clearly shown in Figs. 2 and 3 and is adapted to abut directly against the door 2. The forward end of casing 3 is provided with a rectangular opening 5 and at its rear is provided with another opening so that a latch bar may move longitudinally through said casing 3. That portion of the latch bar which moves through opening 5 is of rectangular cross-section and is provided with a vertically extended opening therethrough which is designated 6 and immediately adjacent said side opening is slotted or bifurcated as at 7. The opposite end of this latch bar is provided with a stem 8 of circular cross-section for movement through opening in the rear of casing 3. Between the part 9 of the lock bar and the rear wall of casing 3 is arranged a coiled spring 10 for normally causing said latch bar to assume the position shown in Figs. 1, 2, and 3. The lower portion of the latch bar is notched as at 11, see Fig. 4 so that when the latch bar is in retracted position the said notched part is caused to engage with the lower edge of the opening 5 in casing 3. The latch bar is brought to this position by operating handle 12 which is horizontally disposed and is pivoted as at 13 between a pair of lugs 14 formed integral with the outer face of casing 3. Pivottally arranged in the bifurcated part of the latch bar is a roller 15 which in the closing of the door 2 is adapted to ride over the surface 25 of keeper 16 to release the latch bar and cause the roller 15 to seat within the keeper, as clearly shown in Fig. 2. To set the latch bar the handle 12 is moved outwardly so that the cam 17 of said handle which engages within the opening 6 of the latch bar may cause the latch bar to recede until the notched part of the latch bar engages the edge of opening 5 as previously described. It will be understood that this latching attachment will automatically latch a refrigerator or other door 110

when the roller 15 engages the surface 25 of keeper 16. Thus, if the handle 12 has not been moved to set the latch bar in latched position and the door is partly open, the door 5 may be closed and latched by merely pushing it shut since the latch bar will recede sufficiently under the tension of spring 10 to become latched with respect to the keeper after a door is fully closed.

10 Having thus described my invention, what I claim as new and desire to secure by Letters Patent, is:

In a latching device the combination of a housing and a door arranged in parallelism therewith, a casing having an open back secured directly to said door, said casing having at one end a squared opening and having mounted for longitudinal movement therethrough, a spring pressed latch-bar, the 20 longitudinal axis thereof being arranged at an inclination with respect to the outer surface of the door, which latch-bar is of rectangular cross-section at its forward end having an opening 6, a bifurcated part 7, the

opposite end of said latch-bar being of circular cross-section, that end of said latch-bar adjacent said bifurcated part being notched at 11 for engaging with the squared opening in said casing in retracted position of said latch-bar, a roller mounted in said 30 bifurcated part, a keeper secured to said housing with which keeper the end of said latch-bar carrying said roller, is adapted to cooperate, a pair of lugs secured to the outer face of said casing, a longitudinally arranged handle pivoted between said lugs for causing tilting of said latch-bar, said handle having a laterally extended cam portion for engaging within said opening 6 of said latch-bar, and a right angle part arranged between 40 said roller and opening 6 and movable through the part 5 and with which said cam portion contacts in locked position of said latch-bar.

In testimony whereof, I have hereunto 45 signed my name.

THOS. O. SCHRADER.
